UNITED STATES PATENT OFFICE.

WILLIAM HENRY PRITCHETT, OF SAN DIEGO, CALIFORNIA.

AIR VALVE AND FUEL CUT-OFF.

Application filed May 4, 1927. Serial No. 188,803.

The present invention relates to improvements in gasoline regulators and has for an object certain improvements over the invention shown and described in my prior Patent 5 No. 1,627,458, granted May 3, 1927.

The primary object of the invention is to effect an economy in the amount of fuel consumed per mile of travel of the automobile.

An incidental object is to accomplish the 10 above result by means of a compact, inexpensive and simply operated and controlled device, the construction of which enables it to be incorporated in the intake manifold of an internal combustion motor without requiring 15 any alteration or modification in standard practice and construction.

A further object of the invention is to provide an improved device which will secure complete combustion of the gasoline; which 20 will properly dilute the mixture passing from the carburetor to the intake manifold; and which will further act to properly atomize the fuel mixture prepared by the carburetor.

With the foregoing and other objects in 25 view, the invention will be more fully described hereinafter, and will be more particularly pointed out in the claims appended hereto.

In the drawings, wherein like symbols refer 30 to like or corresponding parts throughout the several views,

Figure 1 is a fragmentary view of a carburetor intake manifold and automobile instrument board with the improved device shown 35 in connection therewith;

Figure 2 is a plan view of the operating device on the instrument board;

Figure 3 is a bottom plan view of the device, showing the mesh gasket;

Figure 4 is an enlarged vertical section 40 taken through the device with the rotor in side elevation;

Figure 5 is a horizontal section; and,

Figure 6 is a view partly in section taken 45 at right angles to Figure 4.

Referring more particularly to the drawings, 7 indicates a carburetor having the attaching flange 8. 9 represents the intake manifold pipe having the attaching flange 50 10, and 11 indicates the instrument board of an automobile or other vehicle.

The instrument board 11 is adapted to receive a control device for operating the gasoline regulator and the latter is incorporated 55 between the carburetor 7 and intake pipe 9, all shown diagrammatically in Figure 1.

For purposes of effecting the attachment, the regulator is made as a unit with a lower attaching flange 12 united as by the bolts or other appropriate fastenings 13 to the carburetor flange 8. Between the flanges 8 and 12, as shown in Figure 3, is preferably mounted a mesh gasket 14, or a gasket having a mesh center to cover the fuel opening or passage. This mesh or foraminous gasket will 60 act to atomize and break up the fuel mixture, including the gasoline vapor and admixed air and a more homogeneous fuel mixture will result. It is an important consideration that this atomizing gasket or other atomizing 65 medium is placed to act just prior to the delivery of the fuel mixture to the improved regulator, whereby the additional air which is operated by means of the improved regulator will be assimilated promptly following 70 the atomizing action to which the fuel is subjected by the screen gasket.

In like manner the upper portion of the fuel regulator is preferably provided with an upper attaching flange 15 united with the 75 flange 10 of the manifold 9, as by the bolts or other fastenings 16.

The regulator is contained in a casing 17 of appropriate size and form, of metal or other appropriate material having the upper and 80 lower flanges 12 and 15 as before referred to and as shown in Figure 4, having an upper hollow neck 18 and a lower hollow neck 19 of preferably the same diameter as the fuel inlet pipe with which these necks are connected. 90 Between the necks is an enlarged chamber for receiving the valve or rotor 20 which is introduced through one end of the preferably cylindrical casing 17, the other end being permanently closed. Cover plate 21, is adapted to effect closure of the open end of the casing after the rotary valve 20 has been introduced, this cover plate 21 being held removably in place as by the use of the screws, bolts or other fastenings 22 which take into 95 threaded sockets 23 or other parts of the casing.

In the upper portion of the cylindrical part or wall of the casing are provided spaced oil holes 24 and 25 for the purpose of introducing from time to time lubricant to the spaced cylindrical portions of the rotary valve which form the annular bearing surfaces upon which the valve is adapted to truly rotate, the rotating movement being restricted by a 100 threaded or other stop pin 26, which projects through the permanently closed head of the 110

casing 17 and into a quadrant groove 27 in one peripheral edge of the rotary member.

The removable cover plate or head 21 is perforated centrally to admit therethrough the 5 trunnion which projects from the adjacent side face of the rotary valve 20, this trunnion being provided with the round inner section 28 which turns within the wall of the opening in the cover plate and a square outer section 29 adapted to fit the socket of a universal joint by which movement is communicated to the rotary valve from the control device on the vehicle instrument board 11.

The internal construction of the valve 20 15 is shown more particularly in Figures 4, 5 and 6 and consists of the spaced annular bearing portions 30 and 31, which extend to opposite sides of the hollow necks 18 and 19. In the intermediate portion between these bearing parts 30 and 31 is formed a through diametric passage 32 adapted as shown in Figure 20 6 to register co-incidently with both upper and lower hollow necks 18 and 19, whereby to afford a through passage of the same cross 25 sectional area as said hollow necks and the intake pipe.

At both sides of the diametric through passage are struck-off segments; of these segments 33 designates a blank portion and 34 30 designates a removed portion of the segment. The chord 35 upon which the segment 33, 34 is struck coincides with one side wall of the through passage 32. The removed portion or space 34 is considerably larger than the blank 35 space 33, which is provided with the right angularly extending walls 36 and 37, of which the wall 36 coincides with the chord 35, and the wall 37 is adapted to register with the wall of the upper hollow neck 18 when the rotary valve is rotated through an angular 40 distance of 90° in a clock-wise direction from the position viewed in Figure 6.

At the opposite side of the through passage 32, the segment formed is a smaller segment than on the side just referred to. Such 45 second segment comprises a blank portion 38 of greater dimensions than the previously mentioned blank portion 33 and a slotted portion 39 extending adjacent the blank portion 38. The truncated upper end portion of the segment is represented by the line 40 which is parallel to the chord 35. The chord line of the second segment is indicated by the line 41, which is diagonal with respect to the passage 32. There is thus left a relatively large space 42 adjoining the chord line 41 and the blank portion 38, which space 42 communicates 55 freely with the passage 32. The truncated upper portion of the second segment forms a 60 part of the through passage 32.

The circumferential area 43 of the blank portion 38 is slightly in excess of the port area or diameter of the air inlet opening 44 made in the side of the casing 17. This air opening is preferably closed by a cover plate

45 secured in place by the screws or other fastenings 46, and having therein perforations 47 with flaring inner and outer ends 48 for the purpose of reducing the sound of the air being drawn by the engine suction through 70 the cover plate 45.

Referring more particularly to Figures 1 and 2, a universal socket member 49 is adapted to fit freely over the squared end 29 of the rotary valve trunnion. The forked arms 50 75 of this universal socket member are provided with the pin 51 upon which the universal block 52 swivels in one direction. This block is traversed also by a second pin 53, the axis of which is disposed at substantially right 80 angles to the axis of the pin 51. The latter pin 53 is carried in the fork of a second companion universal joint member 54 provided with a socket to receive the lower end 55 of an operating shaft 56 extending upwardly and 85 to and through the instrument board 11 where it is provided with a square or other appropriate end 57 to receive the operating handle or member 58, a set screw 59 being employed to effect the attachment of the operating member to the shaft 56.

The operating member is adapted to rotate over a panel or plate 60 having along its upper circumferential edge a table or scale as indicated in Figure 2, over which the index 61 90 of the handle is adapted to be deflected.

The plate 60 is secured to the instrument board and preferably to an under plate 62 by the use of the screws or other fastenings 63, the heads of which may be countersunk in the 100 plate 60 to permit rotation of the handle member 58. This handle member 58 is formed with a socket 64 containing a spring 65, which is held in place, and the tension of which is adjusted, by a threaded plug 66. A ball detent 67 in the socket is pressed yieldably by the coil spring 65 into one of an arcuate series of rounded depressions 68 made in the lower side of the panel plate 60.

In operation, the mixture from the carburetor 7 will pass up through the wire mesh 11 at high velocity, being broken up and atomized and thereafter promptly enter the regulator where such atomized mixture will be met by a blast of air admitted through the lateral port 44, assuming, of course, that this port is open. In Figure 6 the through passage 32 is shown as in complete registry with the fuel intake line, while the blank portion 38 of the rotary valve completely masks the air inlet port 44, it being clear from this figure that the blank segment portion 38 extends to an appreciable distance both above and below said air inlet port 44. In this condition of the parts one end wall of the groove 27 is 120 in engagement with the stop pin 26, restraining further angular movement of the rotary valve except in a clock-wise direction as viewed in Figure 6. This clock-wise movement may take place through an angle of 90°. 125

This 90° movement will bring the blank segment portion 38 over the hollow neck 19, completely and effectually masking the same and cutting off from the internal combustion motor all communication with the carburetor. The blank segment portion 33 will in this position be in the upper portion of the casing with its wall 37 in alignment with the wall of the upper hollow neck 18. In this condition also the lateral air port 44 will be in full open communication with the interior hollow space of the rotary valve body and with the upper hollow neck 18, so that pure air, unaffected by any mixture with the fuel, will be furnished to the engine. The condition of the parts referred to will be particularly advantageous when the vehicle is descending a hill. The shutting off of the fuel conserves the valuable fuel supply, which is otherwise sucked into the motor and discharged at considerable waste. The inlet of the pure air to the motor also serves to check any formation of partial vacuum which would take place, unless either the air or the fuel mixture was allowed to communicate with the motor during its descent. The formation of the vacuum of course tends to draw oil from the crank case up past the piston rings and into the combustion chambers, thus fouling the spark plugs and inducing the formation of carbon. The air furthermore tends to cleanse and cool the cylinders, thus lessening the tendency of the motor to over-heat and an appreciable braking power is obtained, for the reason that the motive power of the automobile has entirely ceased to function, and consequently the friction of all of the moving parts of the engine and automobile tends to bring the car to a stop.

The rotary valve may be turned to any intermediate position between the position shown in Figure 6 and the angular position of 90° therefrom already referred to. On the initial movement in a clock-wise direction from the position occupied in Figure 6, the spaces 34 and 42 will be gradually moved into the fuel passage as the through passage 32 is shifted partially out of said fuel passage; and it will be noted that the arrangement of the section 38, 39 is such that the slotted portion 39 will move into registry with the air opening 44 before the blank portion 38 begins to cut off the port area of the lower hollow neck 19. The objectionable audible sound that would ordinarily be produced by the inrush of air through the port 44 is reduced or entirely eliminated by the numbers of small perforations 47 in the cover plate 45. As the blank segment portion 38 is rotated further, the port area 19 is diminished in proportion to the angular movement given the rotary valve in a clock-wise direction and the amount of the fuel admitted to the engines is diminished accordingly, while the proportion of additional air from the atmosphere is correspondingly increased, so that a leaner mixture is produced. The slotted portion 39 will admit only a restricted quantity of air and this quantity or mass of air will increase or diminish as the rotary valve is rotated in clock-wise or counter-clock-wise direction. The slot can be made wider or narrower to accommodate the displacement of various motors. The idea involved is to let in a restricted quantity of air initially through the slotted part 39 before the blank segment 38 begins to cut down the port area of the fuel passage. In this way to a limited extent the suction demands of the engine are transferred from the carburetor nozzle to the external atmosphere and a restricted dilution of the fuel is had. When the rotary valve has been turned through a certain distance in a clock-wise direction from the position shown in Fig. 6, the upper end of the wall 40 will have reached the upper portion of the air-port 44 and the entire slotted portion 39 will then be in register with the air port 44. The entire area of the air port 44 is now in readiness to be exposed. Also the entire area of the hollow neck 19, which is still fully open, is in readiness to be fully closed. A further revolution of the rotary valve will simultaneously fully open the air port 44 and fully close the hollow neck 19. By the gradual registration of the slotted portion 39 with the air port 44 during the first 45 degrees of revolution of the rotary valve, a nice regulation of air admitted is secured.

The rotation of the valve is conveniently attended to by the driver from his seat in the vehicle by manipulation of the handle 58 in accordance with the table as pointed out by the index 61. The handle will remain in any angularly adjusted position by reason of the engagement of the detent ball 67 in a depression 68. In operating the device, the motor is started and after being warmed is allowed to run at a predetermined speed, the rotary valve is then gradually turned clock-wise, thus gradually bringing the slotted portion 39 into register with the air port 44 until the motor shows signs of sputtering, whereupon the rotation of the valve is reversed a small angular distance, thereupon the motor will be observed to operate smoothly and with great economy of fuel.

A lock such as indicated at 70 in Figure 2 may, if desired, be associated with handle 58, this lock being arranged to be secured in locked position only when the rotary valve is in such position that the fuel supply is entirely cut off; that is, when the blank segment portion 38 is over the hollow neck 19. In this position the handle 58 will also be over two of the screws 63, so that the plate 60 cannot be removed.

It will be obvious that many changes in the construction, combination and arrange-

ment of parts could be made, which could be used without departing from the spirit of my invention, and I do not mean to limit the invention to such details, except as particularly pointed out in the claims.

Having thus described my invention, what I claim and desire to secure by Letters Patent of the United States is:—

1. An air valve and fuel cut-off comprising a casing having fuel inlet and outlet openings and a lateral air port, a rotary valve mounted in said casing and having a substantially diametric through passage with a segment at one side composed of a relatively small blank portion and a relatively large open portion extending from the through passage to the periphery of the valve, said valve body having at the other side of said passage a smaller segmental portion composed in part of a blank segment part having its chord line diagonal to the chord line of the first-mentioned segment and angular to the axis of the through passage, said last-named segment also having a slotted portion with its chord line extending substantially parallel with the chord line of the first segment, said valve body having a space between said blank portion and the through passage, said blank segment part being adapted in one position of the valve to completely mask the lateral air port and in another position to completely mask the fuel inlet opening.

2. An air valve and fuel cut-off comprising a casing having inlet and outlet ports and an air port, a solid rotary valve body mounted in said casing and having a through passage for establishing communication between said inlet and outlet ports, said valve body having at one side of the through passage a blank wall portion adapted to mask and unmask the air port on angular adjustment of the valve body, said valve body having an open space adjoining the blank wall portion and between the blank wall portion and said through passage whereby to maintain the inlet port open for an interval during which the air port is uncovered by the angular shifting of said blank wall portion toward the inlet port, said valve body also having a slotted portion communicating with the through passage and opening through the periphery of the valve body, said slotted portion adjoining the blank wall portion at the side thereof opposite said open space and positioned to progressively register with said air port as the valve body is rotated in one direction, said valve body having at the opposite side of the through passage a cut away portion connecting with the through passage and opening through the periphery of the valve body for setting up at all times communication between the through passage and the outlet port.

WILLIAM HENRY PRITCHETT.
